US00D630071S

(12) **United States Design Patent**
Krumpe et al.

(10) **Patent No.:** **US D630,071 S**
(45) **Date of Patent:** **** Jan. 4, 2011**

(54) **FASTENING TOOL**

(75) Inventors: **Geraint Krumpe**, Chicago, IL (US);
Michael Reedy, Chicago, IL (US);
Victor Hoernig, Lowell, IN (US); **Man Ki Yoo**, Skokie, IL (US); **Gregg J. Malanga**, Wayne, NJ (US); **Steven J. Mandel**, New York, NY (US)

(73) Assignee: **Arrow Fastener Co., LLC**, Saddle Brook, NJ (US)

(**) Term: **14 Years**

(21) Appl. No.: **29/358,042**

(22) Filed: **Mar. 22, 2010**

(51) LOC (9) Cl. **19-02**

(52) U.S. Cl. **D8/49**

(58) **Field of Classification Search** D8/48, D8/49, 50, 61, 68, 69, 70; D19/72, 73, 65, D19/69, D21/532; D24/145; 7/158, 160; 227/4, 5, 6, 7, 8, 120, 127, 128, 131, 132, 227/134, 144, 156, 175.1; 606/139, 143, 606/153, 219

See application file for complete search history.

(57) **CLAIM**

The ornamental design for a fastening tool, as shown and described.

DESCRIPTION

FIG. 1 is a perspective view thereof;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines shown in the drawings represent unclaimed portions of the fastening tool and form no part of the claimed design.
